UNITED STATES PATENT OFFICE.

GEORGE C. WRIGHT, OF NEW YORK, N. Y., ASSIGNOR TO E. S. HIGGINS & CO., OF SAME PLACE.

DESIGN FOR A CARPET-PATTERN.

Specification forming part of Design No. 5,607, dated March 5, 1872.

Specification describing a Design for Carpets, invented by GEO. C. WRIGHT, of New York, county of New York and State of New York.

The nature of my design is fully represented in the accompanying photographic illustration, to which reference is made.

A represents a mottled ground. B represents a section of the border; C, a section of frame composed of diagonal stripes, alternately dark and light shading, inclosed between two perpendicular stripes, the inside one narrow, the outer one somewhat wider; one-half of the wide stripe being light shading, the rest dark. I am aware that carpet-patterns composed of mottled ground and bordered with stripes or frame-work is not new, and lay no

claim to that feature. The distinctive character of my design is found in the diagonal stripes or bands, alternately dark and light shading, in combination with the perpendicular lines and stripes which are wrought into the border, surrounding or bordering a mottled ground.

What I claim as my invention is—

A design for carpets in which the border is composed of perpendicular and diagonal stripes, in combination with a mottled ground, substantially in the manner above described.

GEORGE C. WRIGHT.
